Inventor
EDWARD J. BROOKS,
By his Attorney
Ed. J. Brooks.

UNITED STATES PATENT OFFICE.

EDWARD J. BROOKS, OF EAST ORANGE, NEW JERSEY, ASSIGNOR TO E. J. BROOKS & CO., OF NEW YORK, N. Y.

SEAL.

SPECIFICATION forming part of Letters Patent No. 323,849, dated August 4, 1885.

Application filed May 25, 1885. (No model)

To all whom it may concern:

Be it known that I, EDWARD J. BROOKS, a citizen of the United States, residing at East Orange, in the State of New Jersey, have invented a new and useful Improvement in Seals, (W².) of which the following is a specification.

My present invention belongs to improvements in those press-fastened seals each of which is composed of a flexible shackle of wire and a seal-disk of soft metal, preferably lead, adapted to embrace the shackle ends and to be solidified around them to fasten the seal. To prevent the withdrawal of either shackle end without such mutilation or defacement of one of the parts as would lead to detection, "anchoring" devices on the shackle end or in the seal-disk are essential in most seals, and have been heretofore formed in various ways.

In common with my inventions set forth in United States Patents No. 179,260, dated June 27, 1876, and No. 192,735, dated July 3, 1877, the general object of my present invention is to provide single shackle-wire with effective anchoring or withdrawal-resisting devices in such a way that they serve additionally as "detector" devices to indicate genuine shackles, and thus prevent or insure the detection of any substitution of a new shackle for one that has been broken in tampering with a seal.

The special objects of the present invention are, first, to produce a very light detector-wire, more secure than cable-wire, and adapted to be more cheaply produced than either of those styles set forth in said Patents No. 179,260 and No. 192,735; and, secondly, to produce, with the aid of such wire, a superior thin and cheap "cast-in" seal.

This invention consists, first, in a hard-metal shackle of fine single wire, provided with permanent sharp bends in a single plane, forming zigzag withdrawal-resisting surfaces, in combination with a soft-metal seal-disk embracing or adapted to embrace the same; and, secondly, in a cast-in seal composed of a soft metal seal-disk having a single threading-hole, and a hard-metal shackle of light single wire having a straight end provided with a bent-up anchoring enlargement cast fast in the seal-disk, and a zigzag threading end to occupy said threading-hole, as hereinafter more fully set forth.

A sheet of drawings accompanies this specification as part thereof.

Figure 1 of these drawings is an elevation of the shackle and seal-disk of my said cast-in seal, straight, as it leaves the factory, the seal-disk being shown in dotted lines to expose the anchoring device of the cast-in shackle end. Fig. 1' shows magnified face and end views of its zigzag threading end. Fig. 2 is 60 a face view of the seal applied to a pair of car-door staples and ready for the seal-press. Fig. 3 represents a like view thereof pressed; and Figs. 4 to 8, inclusive, represent modifications of the shackle, as hereinafter described. 65

Like letters of reference indicate corresponding parts in the several figures.

A represents the shackle, B the seal-disks, and C C a pair of car-door staples, the separation of which is prevented or manifested by 70 the pressed seal, Fig. 3. The shackle A, in either of its forms, is of fine (thin) or relatively-fine wire of hard metal, preferably iron, provided with permanent sharp bends in a single plane, forming short rigid withdrawal-resisting 75 portions at opposing angles, or zigzag at one or each end, z, of the shackle. (See Fig. 1'.) These shackle ends z are adapted to be readily threaded through thin seal-disks, to hold effectively in the pressed-seal disk without change of form, and to manifest the genuineness or fraudulency of shackles found in the seals of "roads" using this invention. 80

In the preferred species represented by Figs. 1, 2, and 3, and in those modifications thereof represented by Figs. 4 and 5, the shackle A has one "zigzag" threading end, z, and at its other extremity a straight end, a, provided with a bent-up anchoring enlargement, b, like those set forth and claimed in said Patent No. 90 192,735. So constructed, this end is adapted to be inserted in a seal-disk mold, so that the escape of lead around it may be easily prevented, as the straight fine wire is all that passes through the walls of the mold, and said 95 anchoring enlargement forms a most effective hold within the seal-disk when this end is so cast in.

The soft-metal seal-disk B of the cast-in seal, preferably of lead, is cast fast on the straight 100 end a of the shackle A, with the anchoring enlargement b in central position, and is pro-

vided with a threading-hole, h , Fig. 1, to receive the zigzag threading end z . After passing said threading end z through the staples C or the like, it is threaded through the 5 seal-disk, as represented by Fig. 2, and the latter is then pressed, and in this act provided with lettering or other distinguishing marks, d , as represented by Fig. 3. The improved seal shown in this figure is pressed by 10 means of my "roller" seal-press, patented June 2, 1885. The zigzag construction, adapted to be extended in length as far as may be desired with little or no additional cost, renders these improved seals peculiarly well adapted 15 for use in connection with said seal-press.

In said modifications, represented by Figs. 4 to 8, inclusive, the fineness of the wire and the shape and extent of the sharp angular bends vary without departing from the construction, mode of operation, and advantages 20 hereinbefore set forth.

Those shackles represented by Figs. 6, 7, and 8, each having two of the zigzag ends z , are especially designed for use in seal-disks 25 having pairs of threading-holes, examples of which are shown in said Patents No. 179,260 and No. 192,735.

Having thus described my said improvement in seals, (W^2), I claim as my invention, and desire to patent, under this specification— 30

1. In combination with a soft-metal seal-disk, a detector-shackle of fine single wire, of hard metal, having permanent sharp angular bends in a single plane, forming short rigid withdrawal-resisting portions at opposing angles, or zigzag, as herein specified, for the purposes set forth. 35

2. The within-described improved seal, comprising a fine single wire of hard metal, having a zigzag threading end formed by permanent sharp bends in a single plane, and a straight end provided with a bent-up anchoring enlargement, in combination with a soft-metal seal-disk cast fast on said straight end around said anchoring enlargement, and having a 40 45 threading-hole to receive said threading end, substantially as herein specified.

EDWARD J. BROOKS.
